EXTENSIBLE SHAFT

Willie M. Shoffner, Dayton, Ohio

Application October 24, 1947, Serial No. 781,961

2 Claims. (Cl. 64—1)

1

This invention relates to extensible shafts for drivingly connecting a driving apparatus to a driven device.

The device has particular application in an apparatus wherein a single power source is adapted to be connected to one of a plurality of driven devices interchangeably so that any one of a plurality of devices can be driven by the single power source at the will of an operator.

One of the problems in providing an extensible shaft of the type that is adapted to connect a single power source to a plurality of driven devices interchangeably is that the distance between the driving connection and the driven connection varies when changing from one to another of a plurality of different kinds of mechanisms. Also, not only does the distance change between the power source and the driven devices but the height of the drive shaft of the driven devices relative to the drive shaft of the power source varies. Thus, for an application of this kind it is necessary to provide a driving shaft which has a considerable degree of extensibility and will function properly regardless of the angle at which it is positioned between the power source and the driven device.

One of the principal applications of the invention is on a power driven apparatus for sheet metal work wherein a plurality of individual forming tools are adapted to be interchangeably connected with the power source so that the operator can at will drive any one of a number of sheet metal forming tools from a common power source.

In sheet metal shops it is and has been for many years the conventional practice to use individual sheet metal forming tools for various forming operations. These tools are all hand-driven by a crank, and all of the sheet metal shops have standard types of sheet metal forming tools which have been purchased on the market over a long period of years.

These tools are of various makes and styles so that there is no regular position from which the drive shaft extends. The only thing common among the tools is the fact that they all have a drive shaft that extends from one end of the forming tool to receive a handle which can be operated manually.

The extensible shaft of this invention is therefore adapted to extend between any one of a number of various makes and styles of sheet metal forming tools and a common power source, the sheet metal forming tools being positioned upon a rotatable table that may be rotated with respect

2

to the power source to bring any one of a number of tools into substantial alignment with the drive shaft of the power source.

It is therefore an object of this invention to provide an improved simplified form of extensible shaft that may be positioned between a prime power source and any one of a number of individual tools selectively at the will of an operator.

Still another object of the invention is to provide an extensible shaft wherein the connection between the power source and the driven apparatus is maintained by a resiliently acting member which will take up all end-play between the power source and the driven apparatus that may result from any varying distances occasioned by transferring the power source from one driven apparatus to another.

Still another object of the invention is to provide a telescoping extensible power shaft that is provided with a universal joint at each end of the power shaft, and is further provided with a device for attaching one of the universal joints to a power source and the other universal joint to a driven device in a detachable manner.

Further objects and advantages will become apparent from the drawings and the following description.

In the drawings:

Figure 1 illustrates a tool stand on which the extensible shaft of this invention is used.

Figure 2 is a perspective elevational view of the extensible shaft of this invention.

Figure 3 is an elevational view illustrating a use of the extensible shaft.

Figure 4 is an elevational view illustrating an additional use of the extensible shaft.

Figure 5 is a cross-sectional view of the extensible shaft.

Figure 6 is a cross-sectional view taken along line 6—6 of Figure 5.

Figure 7 is a cross-sectional view taken along line 7—7 of Figure 5.

To illustrate the manner of use of this invention, in Figure 1 there is shown a tool stand 10 having a rotatable table 11 which carries a plurality of sheet metal forming tools 12, 12a, 12b, 12c, 12d and 12e. Each of the forming tools has its drive shaft designated 13, 13a to 13e inclusive.

A power source consists of an electric motor 14 having a geared head drive 15. The extensible shaft 20 of this invention is adapted to extend between the drive shaft of the geared head drive 15 and any one of the power tools 12, 12a to 12e inclusive. The table 11 is adapted to be indexed

around the power source 14, and is retained in indexed position by means of the member 16 which aligns roughly the location of the forming tool with reference to the drive shaft of the geared head drive 15.

From the array of forming tools carried on the table 11 it will be appreciated that considerable flexibility is required to provide for a driving connection between the geared head drive 15 and the various forming tools.

For example, in Figure 3 the extensible shaft 20 extends between the forming tool 12b and the geared head drive 15. In this instance the drive shafts of the power source and of the forming tool are in substantial alignment, the extensible shaft thus being disposed substantially horizontally.

However, in Figure 4 the power source 15 is connected with the forming tool 12, and in this instance it will be noted that the extensible shaft is required to operate at a considerable angle.

The detail construction of the extensible shaft is more particularly shown in Figures 2 and 5. The shaft consists of a hollow cylindrical body member or tube 21 that has one end thereof swaged into the form of a square end 22.

A square shaft 23 is positioned within the interior of the tube 21 and has the end 24 extending through the squared end 22 of the tube 21. The opposite end of the square shaft 23 is swaged to form a circular head 25 that slidably fits the interior of the tube 21.

One end of the tube 21 carries a cap 26 retained on the tube by means of set screws 27. This cap has a pair of ears 28 between which a square block 29 is positioned. Pins 30 retain the square block in position between the ears 28. The cap 27 thus forms one part of a universal joint.

The other part of the universal joint consists of a U-shaped body 31 having a pin 32 extending through the body and the square block 29. A projection 33 extends from the body 31 and carries a 12-point socket 34, the socket thus being able to receive both a hexagonal as well as a square shaft. The socket is retained on the projection 33 by means of a set screw 35.

A compression spring 36 extends between the cap 26 and the head 25 to urge the square shaft 23 outwardly of the tube 21, to extend the length of the telescoping type of extensible shaft.

The extending end 24 of the square shaft 23 receives a body member 40 having a pair of ears 41 between which a block 42 is positioned and is pivoted upon the pins 43, thus forming one part of a universal joint.

The other part of the universal joint is provided by a cylindrical body 45 having the ears 46, a pin 47 extending through the block 42.

The body 45 is adapted to be secured to the drive shaft of the power source, and to this end it is provided with an internal bore 48 and a set screw 49.

The member 40 is retained on the end of the shaft 23 by means of set screws 50.

While the device disposed and described here-

in constitutes a preferred form of the invention, yet it will be understood that those modifications that fall within the scope of the appended claims are intended to be included herein.

Having thus fully described my invention, what I claim as new and desire to secure by Letters Patent is:

1. An extensible shaft unit comprising, a tubular body member having a squared end of reduced size, a square shaft within the body member and slidably extending through said squared end and having an enlarged head at the end thereof within said body member to prevent removal of said shaft through said squared end and slidably engaging the tubular portion of said body member a substantial spaced axial distance from the squared end of said body, a universal joint on the extending end of said shaft, a closure member on the end of said body member opposite that of the squared end and having a universal joint as a part thereof one of said universal joints including a splined member, and a spring under compression within said body member between said closure member and said head on said shaft to urge the shaft outwardly through the squared end of said body member.

2. An extensible shaft unit comprising, a tubular body member having a squared end of reduced size, a square shaft within the body member and slidably extending through said squared end and having a cylindrical enlargement at the end thereof within said body member to prevent removal of said shaft through said squared end, and slidably engaging the tubular portion of the body member, a universal joint on the extending end of said shaft, a closure cap member on the end of said body member opposite that of the squared end and forming a part of a universal joint, one of said universal joints including a splined member, and a spring under compression between said closure member and said cylindrical enlargement on said square shaft to urge the shaft outwardly through the squared end of said body member.
